(57) CLAIM

The ornamental design for a handle for cooking vessels, as shown and described.

DESCRIPTION

FIG. 1 is a top plan view of a handle for cooking vessels showing my new design;

FIG. 2 is a right side view thereof, the left side view being a mirror image;

FIG. 3 is a bottom plan view thereof;

FIG. 4 is a front view thereof;

FIG. 5 is a rear view thereof;

FIG. 6 is a top, side perspective view thereof;

FIG. 7 is a bottom, side perspective view thereof;

FIG. 8 is a top plan view of an alternate embodiment of FIG. 1;

FIG. 9 is a right side view of FIG. 8, the left side view being a mirror image;

FIG. 10 is a bottom plan view of FIG. 8;

FIG. 11 is a front view of FIG. 8;

FIG. 12 is a rear view of FIG. 8;

FIG. 13 is a top, side perspective view of FIG. 8; and,

FIG. 14 is a bottom, side perspective view of FIG. 8.
